BALANCER OR LEVELING MECHANISM FOR
GASHOLDERS

John H. Wiggins, Chicago, Ill.

Application December 13, 1945, Serial No. 634,806

3 Claims. (Cl. 48—176)

1

This invention relates to gas holders of the type that comprise a tank, or equivalent stationary part, a vertically-movable roof or bell that rises and falls, and thus varies the internal volume of the gas space of the gas holder, and a balancing mechanism combined with said bell in such a way as to maintain the bell in a level position during the rise and fall of same.

The main object of my invention is to provide a leveling mechanism for gas holders, which, in addition to being provided with a double wheel, or a wheel having a wide traction surface over which two flexible members travel side by side, is equipped with vertically-movable guide wheels carried by the bell and arranged so that said flexible members travel under said guide wheels. Other objects and desirable features of my invention will be hereinafter pointed out.

Figure 1 of the drawings is a vertical transverse sectional view of a gas holder equipped with a balancer or leveling mechanism embodying my present invention.

Figure 2 is a fragmentary elevational view of the left hand side of the gas holder shown in Figure 1.

Figure 3 is a fragmentary elevational view of the right hand side of the gas holder shown in Figure 1; and

Figure 4 is a top plan view of the gas holder shown in Figure 1.

In my improved balancer or leveling mechanism, the cables or equivalent flexible members that are used to prevent incipient tipping of the bell and to maintain the bell in a level position, lead downwardly from the bell, instead of leading upwardly, and said cables travel under vertically-movable guide wheels carried by the bell before said cables converge at a double wheel or pulley, over which said cables travel side by side at a point in advance of the counterweight that holds the cables taut. Also, in my improved leveling mechanism herein illustrated one of the cables or equivalent flexible members used to maintain the bell in a level position, extends transversely across the interior of the tank of the gas holder. Thus, it will be seen that in my improved mechanism herein illustrated, all of the wheels, pulleys or sheaves used to sustain and guide the cables or equivalent flexible members that transmit the load of the counterweight to the bell, are disposed at a point lower than the lowest point reached by the bottom edge of the bell when it moves downwardly, instead of being located in an elevated position above the highest point reached by the top of the bell when

2

it moves upwardly. Such a design is desirable, in that it eliminates high towers or equivalent upwardly-projecting pulley or wheel supports on the tank side wall; it overcomes the necessity of having one or more cables of the leveling mechanism extend circumferentially around the exterior of the side wall of the tank; and the vertically-movable guide wheels carried by the bell make it possible to reduce the load of the counterweight by one-half and still get the same balancing force applied to the bell.

In the accompanying drawings, which illustrate the preferred form of my invention, the reference character 5 designates the stationary side wall of the tank of a gas holder equipped with a vertically-movable bell A, whose depending skirt or side wall portion A' is arranged in telescopic relationship with the side wall 5 of the tank. Any suitable means may be used to seal the space between the tank side wall and the depending skirt portion of the bell, such, for example, as a conventional flexible sealing element B attached to the tank side wall and to the depending skirt portion of the bell.

My improved leveling mechanism, in its simplest form, comprises two cables or equivalent flexible members E and F attached to opposite ends of a diameter of the tank of the gas holder, preferably to lugs 8 and 9, respectively, 15 located on the exterior of the side wall 5 of the tank at a point lower than the bottom edge of the skirt portion A' of the bell when the bell is in its lowermost position, shown in full lines in Figure 1. The left hand cable E leads downwardly from its attaching lug 8, and passes under a vertically-movable guide wheel 2 carried by the bell, thence upwardly over a double wheel 1 mounted on the tank side wall 5, and thence downwardly from said double wheel 1 to a counterweight H, the double wheel 1 being mounted on a horizontally-disposed support 6 that projects laterally from the tank side wall 5, as shown in Figure 1. The double wheel 1 consists of a single member rotatably mounted on a supporting shaft, and provided with a relatively wide traction surface, or with a plurality of cable grooves disposed so that a plurality of cables or equivalent flexible members can travel over said wheel side by side. The right hand cable F leads downwardly from its attaching lug 9 and passes under a vertically-movable wheel 4 carried by the bell, thence upwardly over a guide pulley 3 mounted on the tank side wall 5, and thence transversely across the interior of the tank to the double wheel, over which said cable

F leads downwardly to the counterweight H, the guide wheel 3 being mounted on a support 7 that projects laterally from the tank side wall.

The portion of the cable F that extends transversely across the tank, is preferably supported by a guide G on the interior of the tank that prevents said cable from sagging, and means of any suitable kind is provided for preventing the tank side wall from leaking at the points where the cable F passes through said side wall. In the form of my invention herein shown the guide G is formed by a horizontally-disposed, tubular member on the interior of the tank, whose ends are attached in a gas and liquid-tight manner to the tank side wall 5, the cable F running through said tubular guide G from the right hand guide wheel 3 on the exterior of the tank side wall to the left hand double wheel 1 over which the cables E and F travel side by side, in advance of the point where said cables are attached to the counterweight H. Preferably, the cable guide G is suspended from the tank side wall 5 by rods 10 equipped with turnbuckles 11, attached at their lower ends to intermediate portions of the cable guide G, and attached at their upper ends to the top edge portion of the tank side wall.

Any suitable means may be used to mount the vertically-movable guide wheels 2 and 4 on the bell A. In the structure herein illustrated the wheel 2 is rotatably mounted on a horizontally-disposed shaft carried by a pair of vertically-disposed posts C attached to the skirt portion A' of the bell, and projecting downwardly from same, and the vertically-movable guide wheel 4 is similarly mounted on a pair of posts D that project downwardly from the skirt portion of the bell. In order that the bell will be balanced in all directions, the leveling mechanism comprises an additional pair of cables E and F, a counterweight H, and co-acting wheels or pulleys 1, 2, 3 and 4, arranged at right angles to the cables, and co-acting pulleys and counterweight, shown in Figure 1, so as to cause the leveling mechanism to act directly on the bell at four different points separated from each other by angles of 90°.

In my improved leveling mechanism, each of the weights H holds its co-acting cables E and F in sufficiently tight frictional engagement with their co-acting double wheel 1 to cause one cable to instantly become tighter, in the event the bell starts to tip, thereby effectively preventing incipient tipping of the bell.

The vertically-movable guide wheels 2 and 4 on the bell, under which the cables travel, make it possible to reduce the load of said weights by one-half, and still get the same balancing force applied to the bell. During the vertical movement of the bell, indicated by dotted lines in Figure 1, each of the weights H moves twice as far as the bell. As the bell rises, the cables E and F of each set exert the same force on the bell, so long as the bell remains level. If the bell tips, then most or all of the load of the weight H goes into the cable attached to the low side of the bell.

A leveling mechanism of the kind above described is desirable, in that it comprises no parts that are arranged above the top wall portion of the bell. It is also desirable, in that the cable of each set that leads from its counterweight transversely across the tank, is arranged on the interior of the tank, preferably inside of a horizontally-disposed, tubular guide inside of the tank,

which seals the openings in the tank side wall through which the cable travels.

Having thus described my invention, what I claim and desire to secure by Letters Patent is:

- 5 1. A gas holder, comprising a stationary tank, a vertically-movable bell, a pair of flexible members attached to opposite ends of a diameter of the tank, a double wheel mounted on the tank side wall and provided with a wide traction surface over which both of said flexible members travel side by side, a weight attached to both of said flexible members at a point beyond said double wheel and disposed so as to hold both of said flexible members taut and in tight frictional engagement with said double wheel, and vertically-movable guide wheels on the bell, under which said flexible members travel before converging at said double wheel.
- 10 2. A gas holder, comprising a stationary tank, a vertically-movable bell, a leveling mechanism for said bell comprising a pair of flexible members attached to opposite ends of a diameter of the tank side wall and arranged on the exterior of same, a pair of vertically-movable guide wheels carried by the bell and arranged below the bottom edge of the bell, said flexible members leading downwardly from their point of attachment to the tank side wall and traveling under the vertically-movable wheels carried by the bell, a double wheel on the tank side wall over which both of said flexible members travel, a weight attached to both of said flexible members at a point beyond said double wheel and disposed so as to hold both of said flexible members in tight frictional engagement with the traction surface of said double wheel, and a horizontally-disposed, tubular member extending transversely across the interior of the tank, that serves as a housing for one of said flexible members.
- 15 3. A gas holder, comprising a stationary tank, a vertically-movable bell that constitutes the roof for said tank, said bell projecting upwardly above the side wall of the tank, a single wheel and a double wheel rotatably mounted on stationary supports on the tank side wall at points approximately diametrically opposite each other and below the lowest point reached by the bottom edge of the bell when it moves downwardly, two flexible members attached to the tank side wall at opposite ends of a diameter of said wall, downwardly-projecting supports at the lower end of the bell having guide wheels mounted on same, said flexible members leading downwardly from their point of attachment to the tank side wall, then under the guide wheels at the lower end of the bell, and then upwardly to the double wheel at which said flexible members converge and travel in parallel relation over the double wheel, and a weight attached to both of said flexible members at a point beyond said double wheel, so as to hold both of said flexible members taut and in tight frictional engagement with said double wheel.
- 20 4. A gas holder, comprising a stationary tank, a vertically-movable bell, a leveling mechanism for said bell comprising a pair of flexible members attached to opposite ends of a diameter of the tank side wall and arranged on the exterior of same, a pair of vertically-movable guide wheels carried by the bell and arranged below the bottom edge of the bell, said flexible members leading downwardly from their point of attachment to the tank side wall and traveling under the vertically-movable wheels carried by the bell, a double wheel on the tank side wall over which both of said flexible members travel, a weight attached to both of said flexible members at a point beyond said double wheel and disposed so as to hold both of said flexible members taut and in tight frictional engagement with the traction surface of said double wheel, and a horizontally-disposed, tubular member extending transversely across the interior of the tank, that serves as a housing for one of said flexible members.
- 25 5. A gas holder, comprising a stationary tank, a vertically-movable bell, a leveling mechanism for said bell comprising a pair of flexible members attached to opposite ends of a diameter of the tank side wall and arranged on the exterior of same, a pair of vertically-movable guide wheels carried by the bell and arranged below the bottom edge of the bell, said flexible members leading downwardly from their point of attachment to the tank side wall and traveling under the vertically-movable wheels carried by the bell, a double wheel on the tank side wall over which both of said flexible members travel, a weight attached to both of said flexible members at a point beyond said double wheel and disposed so as to hold both of said flexible members taut and in tight frictional engagement with the traction surface of said double wheel, and a horizontally-disposed, tubular member extending transversely across the interior of the tank, that serves as a housing for one of said flexible members.
- 30 6. A gas holder, comprising a stationary tank, a vertically-movable bell, a leveling mechanism for said bell comprising a pair of flexible members attached to opposite ends of a diameter of the tank side wall and arranged on the exterior of same, a pair of vertically-movable guide wheels carried by the bell and arranged below the bottom edge of the bell, said flexible members leading downwardly from their point of attachment to the tank side wall and traveling under the vertically-movable wheels carried by the bell, a double wheel on the tank side wall over which both of said flexible members travel, a weight attached to both of said flexible members at a point beyond said double wheel and disposed so as to hold both of said flexible members taut and in tight frictional engagement with the traction surface of said double wheel, and a horizontally-disposed, tubular member extending transversely across the interior of the tank, that serves as a housing for one of said flexible members.
- 35 7. A gas holder, comprising a stationary tank, a vertically-movable bell, a leveling mechanism for said bell comprising a pair of flexible members attached to opposite ends of a diameter of the tank side wall and arranged on the exterior of same, a pair of vertically-movable guide wheels carried by the bell and arranged below the bottom edge of the bell, said flexible members leading downwardly from their point of attachment to the tank side wall and traveling under the vertically-movable wheels carried by the bell, a double wheel on the tank side wall over which both of said flexible members travel, a weight attached to both of said flexible members at a point beyond said double wheel and disposed so as to hold both of said flexible members taut and in tight frictional engagement with the traction surface of said double wheel, and a horizontally-disposed, tubular member extending transversely across the interior of the tank, that serves as a housing for one of said flexible members.
- 40 8. A gas holder, comprising a stationary tank, a vertically-movable bell, a leveling mechanism for said bell comprising a pair of flexible members attached to opposite ends of a diameter of the tank side wall and arranged on the exterior of same, a pair of vertically-movable guide wheels carried by the bell and arranged below the bottom edge of the bell, said flexible members leading downwardly from their point of attachment to the tank side wall and traveling under the vertically-movable wheels carried by the bell, a double wheel on the tank side wall over which both of said flexible members travel, a weight attached to both of said flexible members at a point beyond said double wheel and disposed so as to hold both of said flexible members taut and in tight frictional engagement with the traction surface of said double wheel, and a horizontally-disposed, tubular member extending transversely across the interior of the tank, that serves as a housing for one of said flexible members.
- 45 9. A gas holder, comprising a stationary tank, a vertically-movable bell, a leveling mechanism for said bell comprising a pair of flexible members attached to opposite ends of a diameter of the tank side wall and arranged on the exterior of same, a pair of vertically-movable guide wheels carried by the bell and arranged below the bottom edge of the bell, said flexible members leading downwardly from their point of attachment to the tank side wall and traveling under the vertically-movable wheels carried by the bell, a double wheel on the tank side wall over which both of said flexible members travel, a weight attached to both of said flexible members at a point beyond said double wheel and disposed so as to hold both of said flexible members taut and in tight frictional engagement with the traction surface of said double wheel, and a horizontally-disposed, tubular member extending transversely across the interior of the tank, that serves as a housing for one of said flexible members.
- 50 10. A gas holder, comprising a stationary tank, a vertically-movable bell, a leveling mechanism for said bell comprising a pair of flexible members attached to opposite ends of a diameter of the tank side wall and arranged on the exterior of same, a pair of vertically-movable guide wheels carried by the bell and arranged below the bottom edge of the bell, said flexible members leading downwardly from their point of attachment to the tank side wall and traveling under the vertically-movable wheels carried by the bell, a double wheel on the tank side wall over which both of said flexible members travel, a weight attached to both of said flexible members at a point beyond said double wheel and disposed so as to hold both of said flexible members taut and in tight frictional engagement with the traction surface of said double wheel, and a horizontally-disposed, tubular member extending transversely across the interior of the tank, that serves as a housing for one of said flexible members.
- 55 11. A gas holder, comprising a stationary tank, a vertically-movable bell, a leveling mechanism for said bell comprising a pair of flexible members attached to opposite ends of a diameter of the tank side wall and arranged on the exterior of same, a pair of vertically-movable guide wheels carried by the bell and arranged below the bottom edge of the bell, said flexible members leading downwardly from their point of attachment to the tank side wall and traveling under the vertically-movable wheels carried by the bell, a double wheel on the tank side wall over which both of said flexible members travel, a weight attached to both of said flexible members at a point beyond said double wheel and disposed so as to hold both of said flexible members taut and in tight frictional engagement with the traction surface of said double wheel, and a horizontally-disposed, tubular member extending transversely across the interior of the tank, that serves as a housing for one of said flexible members.
- 60 12. A gas holder, comprising a stationary tank, a vertically-movable bell, a leveling mechanism for said bell comprising a pair of flexible members attached to opposite ends of a diameter of the tank side wall and arranged on the exterior of same, a pair of vertically-movable guide wheels carried by the bell and arranged below the bottom edge of the bell, said flexible members leading downwardly from their point of attachment to the tank side wall and traveling under the vertically-movable wheels carried by the bell, a double wheel on the tank side wall over which both of said flexible members travel, a weight attached to both of said flexible members at a point beyond said double wheel and disposed so as to hold both of said flexible members taut and in tight frictional engagement with the traction surface of said double wheel, and a horizontally-disposed, tubular member extending transversely across the interior of the tank, that serves as a housing for one of said flexible members.
